(57) **CLAIM**

The ornamental design for a medical viewing device, as shown and described.

DESCRIPTION

FIG. 1 is a perspective view of a medical viewing device showing our new design;

FIG. 2 is another perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof

FIG. 9 is another perspective view thereof, shown with a handle; and

FIG. 10 is another left side elevation view thereof, shown with the handle.

FIG. 11 is a perspective view of another embodiment of a medical viewing device showing our new design;

FIG. 12 is another perspective view thereof;

FIG. 13 is a left side elevation view thereof;

FIG. 14 is a right side elevation view thereof;

FIG. 15 is a front elevation view thereof;

FIG. 16 is a rear elevation view thereof;

FIG. 17 is a top plan view thereof;

FIG. 18 is a bottom plan view thereof

FIG. 19 is another perspective view thereof, shown with a handle; and,

FIG. 20 is another left side elevation view thereof, shown with the handle.

The broken lines immediately adjacent to shaded areas

depict boundaries of the claim and form no part of the
